United States Patent Office

Des. 215,781

Patented Oct. 28, 1969

215,781

HAIR ROLLER

Robert J. Tolmie, Fairfield, Conn., assignor to Sperry Rand Corporation, New York, N.Y., a corporation of Delaware

Filed July 1, 1968, Ser. No. 12,563

Term of patent 14 years

Int. Cl. D28—03
U.S. Cl. D86—10

FIG. 1.

FIG. 2.

FIG. 3.

FIG. 4.

FIG. 1, is a top plan view of a hair roller showing my new design;

FIG. 2 is a front elevational view thereof with the rear being similar in appearance;

FIG. 3 is a side elevational view thereof as seen from the right in FIG. 2, the side opposite thereto being similar in appearance; and

FIG. 4 is a bottom view thereof.

I claim:

The ornamental design for a hair roller, as shown and described.
